[57] **CLAIM**

The ornamental design for a two-handled shovel, as shown and described.

DESCRIPTION

FIG. 1 is an environmental perspective view of a two-handled shovel showing my new design;
FIG. 2 is a front elevational view thereof;
FIG. 3 is a rear elevational view thereof;
FIG. 4 is a left side elevational view with the right side being a mirror image thereof;

FIG. 5 is a top plan view thereof; and,
FIG. 6 is a bottom plan view thereof.
The broken line showing of the screws is for illustrative purposes only, merely disclosing the types of attachments which can be used, and forms no part of the claimed design. The broken line showing of a person in FIG. 1 is for environmental purposes only and forms no part of the
